CLAIM

The ornamental design for a roller saver container, as shown and described.

DESCRIPTION

FIG. 1 is a perspective view of the roller saver container of my new design showing the covering cap thereof separated from the container body.

FIG. 2 is another perspective view of the roller saver container of my new design showing the covering cap secured in place at the top.

FIG. 3 is a front elevational view thereof.

FIG. 4 is a back elevational view thereof.

FIG. 5 is a left side elevational view thereof.

FIG. 6 is a right side elevational view thereof.

FIG. 7 is a bottom plan view thereof; and,

FIG. 8 is a top plan view thereof.

The even-length broken line defines the bounds of the claim and forms no part of the claimed design.
